UNITED STATES PATENT OFFICE.

KARL O. OLSON, OF CHICAGO, ILLINOIS, ASSIGNOR TO SINGLE SERVICE PACKAGE CORPORATION OF AMERICA, OF NEW YORK, N. Y., A CORPORATION OF NEW JERSEY.

APPARATUS FOR INSERTING CLOSURES IN VESSELS.

1,010,304.

Specification of Letters Patent. Patented Nov. 28, 1911.

Application filed January 27, 1910. Serial No. 540,439.

To all whom it may concern:

Be it known that I, KARL O. OLSON, a citizen of the United States, residing at Chicago, in the county of Cook and State of Illinois, have invented certain new and useful Improvements in Apparatus for Inserting Closures in Vessels; and I do hereby declare the following to be a full, clear, and exact description of the invention, such as will enable others skilled in the art to which it appertains to make and use the same.

This invention relates to means for closing receptacles and has for its object to produce a device of this nature which will more effectually insert the inverted flanged cup-shaped closures into the mouths of paper vessels than the means at present employed.

To these ends the invention consists in the novel details of construction and combinations of parts, more fully hereinafter disclosed and particularly pointed out in the claims.

Referring to the accompanying drawings, forming a part of this specification, in which like numerals refer to like parts in all the views:—Figure 1, is a diagrammatic elevational view partially in section of the well known die plunger press adapted for inserting closures in paper vessels, with my improvement attached thereto; Fig. 2 is a plan view of that portion of the mechanism shown in Fig. 1 lying below the line 2—2; Fig. 3, is a sectional elevational view of the essential portions of the mechanism shown in Fig. 1, but showing the parts in a different position; and, Figs. 4 and 5, are detail views of the lower half of the mechanism and showing the movable ring in its upper and lowest positions respectively.

1 represents any suitable framework supporting the plunger mechanism and comprising a vertically reciprocating cross head 2, a die cutting plunger 3, and a die shaping plunger 4.

5 represents the paper which is fed by suitable means underneath the plungers 3 and 4, and 6 the vertically movable ring shaped die through which the flanged disk closure 7 is forced by the plunger 4, all as is now well known.

The vertically moving ring 6 which for brevity I will hereinafter call a floating ring, is supported by suitable springs 8 and guided as by the rods 9 through suitable guide lugs

10 integral or otherwise attached to the framework 11. This floating ring is also provided with a beveled ring shaped portion 13, terminating in the overhanging lip 14. The beveled portion 13, as the floating ring descends, surrounds and accurately shapes to a circle the upper edge 15 of the vessel 16 to be closed; while the overhanging lip 14 projects over and protects the said upper edge 15 of the body of the vessel 16 from being crushed during the inserting operation, as plainly appears in Fig. 3. It results from this construction, that frangible paper bottles may be readily closed at a rapid rate by machinery without crushing the same, and the mechanism so far disclosed constitutes no part of my present invention. When the die plunger 4, however, descends into the bottle body 16, as indicated in Fig. 3, and after it has forced the closure 7 down into the bottle body, as indicated in Fig. 1; there exists a considerable friction between the outer surface of the plunger 4 and the inner surface of the closure 7. The bottle body 16 is so light and this friction is so great that as the plunger 4 begins to ascend it is liable to carry the bottle body and ring 6 with it. This action is greatly aided by the springs 8 which automatically lift the ring and impart to it a tendency to follow the plunger upward.

Should the bottle 16 lift as indicated, it results that it is removed from its seat on its support 18 and thereby disarranged for other operations which it may be desired to perform on it.

In order to avoid this defect, I provide the floating ring 6 with the projections 20 and 21, preferably in the form of pipes, in order that a liquid may be passed therethrough, as indicated, and I cut slots 22 and 23 in the framework 11 in order to permit the pipes 20 to move up and down with the floating ring 6. To the outside of the framework 11 I preferably pivot as at 25, a lever 26, having the hook 27 adapted to pass over one of the projections as 20, when the latter is in its lowest position, as best indicated in Figs. 3 and 4. The spring 28 may be employed to automatically return the lever 26 into the position shown in Fig. 4, after it has been displaced from such position, as indicated in Fig. 5.

The lever 26 is provided with an extension

31 having the slotted lug 32 in the slot 33 of which plays a pin 34 attached to the reciprocating rod 30 secured to the cross head 2 in any suitable manner.

5 The parts are so timed, that as the cross head descends, carrying with it the plunger 4, the pin 34 will reach the bottom of the slot 33 just after the floating ring 6 has descended to its lowest position, and the said 10 pin 34 will thereupon, cause the hook 27 to take over and to firmly lock in place the pipe 20, as indicated in Fig. 3, thereby holding the floating ring 6 in its lowest position. When the cross head 2 now ascends the pin 15 34 will rise in the slot 33 and will strike the upper end of the same after the plunger has left the mouth of the bottle 16 whereupon the said pin 34 will swing the hook 27 out of its locking position, and permit the pipe 20 and the floating ring 6 to rise into the 20 position indicated in Fig. 1. This cycle of operations is repeated over and over again.

It is often desirable to coat at least a portion of the outer surface of the closure 7 25 with an adhesive before inserting it into the bottle, and when this adhesive is applied to such closures the plunger 4 necessarily gets more or less gummed up therewith, and is, therefore, more liable to raise 30 the bottle body 16 and the ring 6 from its seat than would be the case were no adhesive employed.

My invention, therefore, is of peculiar importance when adhesives are used in connection with machinery for closing bottle bodies, for that it firmly holds the bottle in position by causing the floating ring to act as a stripper no matter how much the friction may be between the plunger 4 and the 40 inside of the bottle mouth.

In the drawings, I have indicated a convenient means for applying adhesive to the closure 7, which consists in openings in the floating ring through which hot paraffin 45 or other adhesive may be fed to the closure 7 just prior to its insertion into the bottle body. The hot paraffin may be conveniently applied from a tank 41 connected with the pipe 21 by means of a flexible connection 42, 50 as illustrated. In order that the hot paraffin may not flow out while the openings 40 are uncovered, I provide a suitable valve device 43 operated by a pin and slot connection 44 and a rod 45 connected with the cross head 55 2, as will be readily understood.

Paraffin, as is well known, is an efficient lubricant and it is also, when applied to paper and allowed to cool a most excellent adhesive. It therefore follows that no gumming occurs on the ring 6 and the plunger 4 when paraffin is used as the adhesive since it merely acts as a lubricant in the operation of the machine. In addition to this, when paper is paraffined, it is much more pliable 60 and easily worked under a die press than is

unparaffined paper. Therefore paraffin is peculiarly adapted for use as the adhesive in connection with this machine.

The parts 44 and 45 are so timed that the valve 43 is opened an instant before the 70 paper closure 7 reaches the ports or openings 40 and it is closed just before the said closure 7 passes the said ports 40. The head of hot paraffin in the tank 41 serves to readily force the same through the ports 40 as 75 soon as the valve 43 is opened.

The hollowed out portion of the ring 6 is preferably closed by an annular ring closure 47 which may be readily removed for the purpose of cleaning the ring, 6, as by inserting 80 a wrench in the holes 48, as will be readily understood.

It is evident that those skilled in the art may vary the details of construction and the arrangement of parts disclosed without departing from the spirit of my invention and, therefore, I do not wish to be limited to such features except as may be required by the 85 claims.

What I claim is:—

1. In a machine for inserting a flanged closure in a vessel body the combination of a reciprocating plunger member fitting said closure and having a tendency to lift said body by reason of its continued contact with the closure after it has been inserted; a die member adapted to move into and out of contact with the vessel body to be closed; and means for holding said die member in contact with said vessel so long as said 90 plunger member has a tendency to lift said body, substantially as described.

2. In a machine for inserting flanged closures in vessel bodies, the combination of a plunger member fitting said closures, adapted to move into and out of contact with the flanges of the closures to be inserted and having a tendency to lift said closures and bodies during said latter movement; a closure forming die member through which 100 said plunger member passes adapted to shape and move into and out of contact with the vessel body to be closed; and means for holding said die member in contact with said vessel bodies so long as said plunger 105 member tends to lift said bodies, substantially as described.

3. In a machine for inserting flanged closures in vessel bodies, the combination of a reciprocating plunger fitting said closures 120 adapted to move into and out of contact with the closures to be inserted and having a tendency to lift said closures and bodies during said latter movement, a reciprocating closure forming die member through which 125 said plunger passes, adapted to shape and to move into and out of contact with the vessels to be closed; and automatic means adapted to lock and hold said die member in contact with said vessels so long as said 130

- plunger has said tendency to lift said bodies, substantially as described.
4. In a machine for inserting flanged closures in vessel bodies, the combination of a reciprocating closure inserting means; a closure and vessel shaping means, the inserting means adapted to fit said closures, the shaping means to contact with the closed vessels, and the inserting means having a tendency 5 to lift the vessels from their seats; and means for holding said shaping means in contact with the closed vessels so long as said lifting tendency exists, substantially as described.
- 10 5. In a machine for inserting flanged closures in vessels, the combination of a reciprocating closure inserting means; a reciprocating closure shaping means; the inserting means fitting said closures and having a 15 tendency to lift the vessels from their seats; means comprising a locking lever for holding said shaping means in contact with the closed vessel so long as said inserting means has said lifting tendency; and means connected with said inserting means for releasing 20 said lever after said inserting means has moved out of contact with said vessel; substantially as described.
- 25

6. In a machine for closing vessels, the combination of a reciprocating plunger; a reciprocating hollow shaping die through which said plunger passes, provided with an opening 40; means to supply an adhesive to the inside of said hollow die; means connected with said die; and locking means 30 adapted to coact with the same to hold said die in its lowest position during a portion of the stroke of said plunger; substantially as described.

7. In a machine for closing vessels, the combination of a reciprocating plunger; a hollow reciprocating die coacting with said plunger provided with an orifice 40; means to feed an adhesive to said die; automatic means to control the flow of said adhesive; and automatic means to lock said die in 35 its lowest position during a portion of the stroke of said plunger, substantially as described.

In testimony whereof, I affix my signature, in presence of two witnesses.

KARL O. OLSON.
